UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

COIL-FORMING APPARATUS.

No. 825,249.

Specification of Letters Patent.

Patented July 3, 1906.

Application filed January 24, 1903. Serial No. 140,350.

To all whom it may concern:

Be it known that I, GEORGE E. STEVENS, a citizen of the United States, residing at Lynn, county of Essex, State of Massachusetts, have invented certain new and useful Improvements in Coil-Forming Apparatus, of which the following is a specification.

My invention relates to coil-forming apparatus, and has for its object the production of a simple and highly-efficient means for winding thin strips of metal on edge into coils of desired length.

Heretofore much difficulty has been experienced in the manufacture of edge-wound coils on account of the tendency of the strip to buckle or fall out of a true helix, due to the unequal strains set up in the strip as it is bent. Moreover, when the coils are formed by winding the successive convolutions in juxtaposition to convolutions previously formed there is a tendency for the outer edges of the convolutions to fall back relative to the inner edges, due to the fact that the outer edge of the strip is contracted transversely, while the inner edge is upset in the operation of bending.

The most effectual method of winding flat strips on edge has been found to consist in the use of a die which supports the strip on both sides until it has passed the forming-point. This method, however, presents a number of mechanical difficulties, such as the introduction of the strip into and through the die to the point of attachment to the mandrel and the liability of rupturing the strip, due to the relatively great friction between working surfaces of the die and the sides of the strip.

According to my invention I provide a mandrel adapted to be received and rotated by the ordinary engine-lathe or boring-mill and a winding-head adapted to coöperate with said mandrel either by having relative axial movement therewith or by means of an auxiliary movable sleeve, whereby the coil is formed in place upon the supporting part. The winding-head is provided with channels and grooves, whereby the strip is independently supported on both sides for a greater or less part of a complete convolution and then discharged therefrom and left either in juxtaposition with the previously-formed coil or separated therefrom, as desired. In order that the strip may be readily introduced into the winding-head, I provide the latter with a

manually-operated part, whereby the point of exit of the coil from the head may be brought into substantial alinement with the point of ingress and after the strip has been inserted restored to its operative position, carrying with it the strip and forming the first convolution.

The invention will be more readily understood by reference to the accompanying drawings, forming a part of this specification, in which—

Figure 1 is a side elevation of a coil-forming apparatus embodying one form of my invention and shown in connection with an ordinary lathe. Fig. 2 is an enlarged horizontal axial section of the apparatus shown in Fig. 1. Fig. 3 is a right-hand elevation of the winding-head. Fig. 4 is a section on line 4-4 of Fig. 2. Fig. 5 is a perspective view of a modified form of the apparatus in which the winding-head is designed to move away from the coil. Figs. 6 and 7 are respectively a top plan and an end elevation of another modification. Fig. 8 is a perspective view of a coiling-head designed to operate upon two strips simultaneously. Fig. 9 is a side elevation, with parts broken away, of a coil-forming apparatus designed for making coils of irregular contour. Fig. 10 is a left-hand elevation of the winding-head shown in Fig. 9. Fig. 11 is a horizontal axial section on line 11-11 of Fig. 9. Fig. 12 is a horizontal section on line 12-12 of Fig. 10. Fig. 13 is a perspective view of a coil-forming apparatus adapted for use upon thick strips, and Fig. 14 is a side elevation thereof.

As shown in Fig. 1, the coil-forming apparatus is designed to be supported by the centers of an ordinary lathe A in the usual manner, the tool-carriage being employed merely as a rest for a part of the winding-head, and the reel C for the strip may be clamped to the bed of the lathe. The coil-forming apparatus consists of a supporting-mandrel 1, which is adapted to be engaged by the lathe-centers, and an axially-sleeved mandrel 2, loosely mounted upon the supporting-mandrel 1 and held from rotation relative thereto by a feather 3. Surrounding the right end of the sleeved mandrel 2 is a shouldered collar 4. The winding-head surrounds the left end of the mandrel 2 and comprises the sleeve 5, having a driving fit at its left end with the supporting-mandrel 1 and is chambered out

for a greater portion of its length to permit the sleeved mandrel 2 to telescope therewith and provided at its right end with a disk-shaped flange 6 and a hardened friction-shoulder 7 at its external right-hand end. Surrounding the flange 6 and a portion of the sleeve 5 is a recessed ring 8, connected by means of set-screws 9 to a guide-plate 10. The guide-plate 10 has an outer periphery like that of the ring 8, and its inner periphery forms a bearing for the friction-shoulder 7, and lying inside of a tangent to the outer periphery is an arm 11, having a passage 12 therethrough for the strip. The right-hand side of the guide-plate 10 has a crown shoulder 13, upon which a sectional retaining-ring 14 is secured by set-screws. The retaining-ring 14 enters a peripheral recess in the adjustable ring 15 and operates to hold the latter in position relative to the other parts of the winding-head. The adjustable ring 15 is provided in its outer periphery with a series of spanner-holes 16, whereby it may be rotated by hand. A conical recess is formed in its right side, and at its left side, near its inner periphery, it is provided with a shoulder 17 for the reception of a flange of the split friction-ring 18, to which the latter is attached by set-screws. The friction-ring 18 is made of hardened steel and has a slot 19 diagonally traversing it for the passage of the strip from the left-hand surface to the right. The slot 19 is normally positioned one hundred and eighty degrees from the point of union of the guide-passage 12 with the forming-passage about mandrel 2. In order to introduce the strip into the winding-head, the adjustable ring 15, to which the friction-ring 18 is attached, is turned backward until the left-hand end of the slot 19 is brought into line with the channel 12, when the strip will pass through the slot 19 with slight difficulty, and the end is then secured to the shouldered collar 4. The adjustable ring 15 is then turned forward to the desired position, where it may be held by the friction between the parts or by clamps. The device being now ready to operate, the mandrels 1 and 2 and sleeve 5 are caused to rotate in unison, while the guide-plate 10 and its associated parts—the recessed ring 8, the adjustable ring 15, and friction-ring 18—are restrained from rotation by the arm 11 engaging the tool-carriage or other stationary part. It is to be noted that the friction-shoulder 7 and the periphery of the sleeved mandrel 2 as they come in contact with the strip move with it at the same speed, so that the friction between said parts and the strip acts to carry it along against the opposing friction of the stationary friction-surfaces on the guide-plate 10 and the friction-ring 18, so that the tensile strain upon the strip is reduced to a negligible quantity and irrespective of the total friction between the friction-surfaces

and the strip. It will accordingly be seen that the winding-head readily operates to forge or draw the strip, so as to prevent the usual distortion of the rectangular cross-section during the coiling operation.

The construction shown in Fig. 5 differs from that above described in that the supporting and sleeved mandrels 1 and 2 are made integral and the winding-head arranged to be traversed to the left by the accumulation of the coil at the right. In the figure is shown one means for clamping the strip to the collar 4, consisting of a lever 20, pivoted at its right end to the collar and normally forced away from a radial shoulder 21 in the collar by a spring 22 and operated to engage the strip by a screw 23, passing therethrough and engaging the collar 4.

The construction shown in Figs. 6 and 7 consists of a supporting-mandrel 1, upon which the shouldered collar 4 is directly mounted, and the movable winding-head. The winding-head is here shown in its simplest form and consists of a split sleeve 25, having a radial friction-surface on its right-hand end, and attached thereto with an intervening space by means of pins 26 is a spring friction-ring 27, having a slot 28. The sleeve 25 is held from rotating by means of an arm 29, attached thereto and engaging some stationary part of the lathe. The arm 29 has a groove 30 in its upper surface, which leads into the intervening space between the split sleeve 25 and friction-ring 27. A plate 31 is connected to the upper surface of the arm 29 by a screw and overlies the groove 30 to hold the strip therein. An adjustable means is applied to the split sleeve 25 to vary its resistance to longitudinal travel along the mandrel, consisting of a screw-bolt 32, passing through lugs 33 on the respective sides of the split sleeve and provided with a spring 34. When the strip is introduced into the winding-head, it is run through the guide-groove 30 and the lower part of the intervening space between the split sleeve 25 and the friction-ring 27 and allowed to project beyond the head a considerable distance. The operator then manually bends the projecting end up through the intervening space and carries it out through the slot 28, connecting it to the shouldered collar 4 in the usual manner. In order to facilitate this manual operation, the strip may be reduced in width at its end; but for most kinds of strips this will be unnecessary.

The winding-head shown in Fig. 8 is designed for winding two strips simultaneously and differs from the construction of Figs. 6 and 7 only in that two grooves 30 and two friction-rings 27, with the corresponding intervening spaces, are provided.

The form of winding apparatus shown in Figs. 9 to 12 is designed for making coils of rectangular contour and consists of a mandrel

1, upon which are fixed two prismatic blocks 36 and 37. Block 36 has a rabbet 38 formed in the periphery of its right-hand face, which serves as a groove for the reception of the strip. The block 37 is somewhat smaller than block 36 and serves as a steadier for the formed coil. A friction-plate 39 is located between the blocks 36 and 37 and is provided with a substantially radial slot 40 for the passage of the coiled strip as formed to the right side of the plate. The plate 39 is carried by a frame 41, provided at its lower end with guides 42 for engaging the ways of the lathe. A reciprocating guide-block 43 is provided to operate with the rabbeted block 36 and is mounted to slide up and down by means of a dovetailed connection with the left-hand side of the frame 41 and is normally pressed upward by springs 44, engaging the lower part thereof and a projection from the frame 41.

In the construction shown in Figs. 13 and 14 an adjustable tension means is shown, consisting of a guide-box 45, having an adjustable slide 46, adapted to be moved and held in adjusted position by screws 47.

What I claim as new, and desire to secure by Letters Patent of the United States, is—

1. In a device for edgewise-coiling flat metal strips, the combination with a winding-mandrel, of a circular winding-head surrounding said mandrel and having provisions for supporting the article to be wound upon both sides through the point of initial bending and substantially a semiconvolution.

2. In a device for edgewise-coiling flat metal strips, the combination with a winding-mandrel, of a winding-head surrounding said mandrel and having provisions for supporting the article to be wound upon both sides through the point of initial bending and substantially a semiconvolution, and for discharging the article as formed sidewise from said head and into juxtaposition with the previously-formed coil.

3. The combination of a winding-mandrel, a winding-head movable relative thereto and provided with friction-surfaces adapted to support the article to be wound upon both sides through the point of initial bending and substantially a semiconvolution, and a side passage-way in one of said friction-surfaces for the discharge of the article as formed.

4. The combination of a winding-mandrel, a winding-head surrounding said mandrel and having entrance and discharge openings for the article to be wound located on diametrically opposite sides thereof, and means to facilitate the introduction of the article into and through said head.

5. The combination of a winding-mandrel, a winding-head surrounding said mandrel and having entrance and discharge openings for the article to be wound located on oppo-

site sides thereof, and means to bring one of said openings into alignment with the other.

6. The combination of a winding-mandrel and a winding-head surrounding said mandrel and provided with a normally stationary friction-surface and a movable friction-surface adapted to travel with the article to be wound from the point of initial bending throughout the greater portion of a convolution.

7. The combination of a winding-mandrel and a winding-head having entrance and discharge openings for the article to be wound located on opposite sides thereof and provided with a normally stationary friction-surface and a movable surface adapted to travel with the article to be wound from the point of initial bending throughout the greater portion of a convolution.

8. The combination of a winding-mandrel and a winding-head comprising a guide-plate adapted to engage the outer edge of the article to be wound, a movable friction-surface to travel with the article, and a normally stationary friction-surface.

9. The combination of a winding-mandrel and a winding-head surrounding said mandrel, consisting of a guide-plate adapted to conduct the article to be wound to the mandrel and to engage the outer edge of said article and hold it in engagement with the mandrel, a movable friction-surface adapted to travel with said article, and a normally stationary friction-ring having a passage for the formed article from the head and provision whereby said ring may be rotated to bring said passage in alignment with entrance to the guide-plate.

10. The combination of a winding-mandrel and a winding-head surrounding said mandrel, consisting of a stationary guide-plate adapted to conduct the article to be wound to the mandrel and to engage the outer edge of said article, a part having movable engagement with said plate and provided with a friction-surface to travel with the article, and a friction-ring supported upon said plate and provided with a passage for the formed article from the head.

11. The combination of a supporting-mandrel, a sleeved mandrel feathered thereto, a telescoping sleeve fixed to one end of said supporting-mandrel and carrying a flange and friction-surface at one end, a stationary guide-plate and a retaining-ring engaging said flange, and a friction-ring rotatably mounted on said plate.

In witness whereof I have hereunto set my hand this 21st day of January, 1903.

GEORGE E. STEVENS.
